UNITED STATES PATENT OFFICE.

CHARLES F. McBEE, OF ATHENS, OHIO, ASSIGNOR TO THE McBEE BINDER CO., A CORPORATION OF OHIO.

LOOSE-LEAF FILE.

1,375,523.

Specification of Letters Patent. Patented Apr. 19, 1921.

Application filed September 25, 1919. Serial No. 326,119.

To all whom it may concern:

Be it known that I, CHARLES F. McBEE, a citizen of the United States, residing at Athens, in the county of Athens and State 5 of Ohio, have invented certain new and useful Improvements in Loose-Leaf Files, of which the following is the specification.

The object of my invention is to produce a loose leaf file which will have all the 10 permanency of a bound volume and yet can be easily and quickly opened and locked, for convenience in removing or adding sheets thereto.

My invention consists of certain details 15 of construction hereinafter set forth, pointed out in my claims, and illustrated in the accompanying drawings, in which:

Figure 1 shows a side elevation view of my file;

Fig. 2 shows a sectional view taken on the line 2—2, in Fig. 1.

Fig. 3 shows a plan view of my file, the parts being open and unlocked, the sheets having been removed and a part of each 25 cover broken away;

Fig. 4 shows a detail view of a modified form of the carrying members; and

Fig. 5 shows a sheet perforated, as would be required, to be carried by the modified 30 carriers.

Referring to the accompanying drawings, the reference numerals 10 and 11 indicate the upper and lower covers of my file, each of which is provided with a hinged portion 35 12 and 13 respectively, which portions are joined by the back 14. At the point of junction of the back with the lower cover, I have provided a hinge joint 15 which is designed to permit the back to fall down 40 and lie flat, and in line with the lower cover, when the file is open.

The numerals 16 and 17 indicate plates which serve the dual purpose of retaining the upper cover and back at right angles to each other, and to extend forwardly from the back to overlap the hinged portion of the lower cover, a recess, or slot, 18 and 19 respectively, opening forwardly, being provided in each plate near its forward end 45 and near its base. These said plates are mounted one near each edge surface of the file, and the filed sheets lie between them.

On the upper surface of the hinged portion of the lower cover I have mounted a

plate 20 with upturned lugs 21 and 22, secured one on each end thereof, said lugs designed to lie inside their respective plates 16 and 17, when the file is locked, and also on the said plate 20 I have secured two, or more, upwardly projecting hollow posts 23 and 24. Each of the lugs 21 and 22 has an elongated orifice and a spring wire, or rod, 25, of a length practically equal to the width of the file is guided as to its ends in said orifices, and passed back of the posts 23 and 24 (which by construction are in the rear of a line drawn between the orifices in the lugs) thus holding said rod in position with a rearward tension on the ends thereof. The slots 18 and 19 are designed to receive the ends of the rod, or wire, and as the plates 16 and 17 are beveled immediately below the said slots the action of pulling the back 14 forwardly and pressing downwardly on it, has the effect of 75 forcing the slots over the rods and causing an engagement and the spring in the rod forces it back to a seat in the slots, thus locking the lower and upper covers at right angles to the back.

The numeral 26 indicates a supporting plate, with posts 27 and 28, designed to telescope within their respective posts 23 and 24, the function of the plate and its posts being not only to assist in retaining the filed 85 sheets on the parts 23 and 24, but to serve as a base, or supporting means for such of the upper sheets as the operator may desire to take off the file, to insert or withdraw a sheet in, or from, the file. Its operation is 90 obvious. It is equally obvious the sheets to be filed are perforated to fit over the posts 23 and 24.

In my modified form shown in Figs. 4 and 5, the sheets contain four or more perforations, and the posts on the lower plate engage a certain set of these perforations while the posts on the upper plate engage a different set of the perforations, the posts of both plates however, being of equal length so 100 that when they are threaded through their respective perforations, they rest against the surface of their companion plate, the papers being held between the plates. The function of the plates and posts, and the 105 results obtained are the same in this modified form as in my preferred form.

Having thus described my invention what

I claim and desire to secure by Letters Patent of the United States is:

1. A loose leaf file comprising a back and upper and lower covers loosely secured together, each of said covers also having a hinge near its inner end; a plate, having orificed flanges on each of its ends, mounted on the upper surface of the lower cover and inside of the hinged portion thereof, said plate also having upwardly projecting hollow posts secured thereto; a wire spring overlying said plate, its ends projecting through the orifices in the flanges, said spring lying on the inner side of the upright posts; right angular plates joining rigidly at right angles the back and the inner hinged portion of the upper cover, each of said plates being provided with recesses to receive the ends of the wire spring and thereby secure the back in right angular position with the inner hinged portion of the lower cover; a carrier plate provided with posts designed to telescope within the upright hollow posts, substantially as shown and described.

2. A loose leaf file comprising a back and upper and lower covers loosely secured thereto, said covers also having hinges near their inner ends; a plate, having orificed flanges on each of its ends, mounted on the upper surface of the lower cover and inside of the hinged portion thereof, said plate also having upwardly projecting hollow posts secured thereto; a wire spring overlying said plate, its ends projecting through the orifices in the flanges, said spring lying on the inner side of the upright posts; right angular plates joining rigidly at right angles the back and the inner hinged portion of the upper cover, each of said plates being provided with recesses to receive the ends of the wire spring and thereby secure the back in right angular position with the inner hinged portion of the lower cover, a carrier plate provided with posts designed to engage their respective perforations in the sheets to be bound, substantially as shown and described.

plates joining rigidly at right angles the back and the inner hinged portion of the upper cover, each of said plates being provided with recesses to receive the ends of the wire spring and thereby secure the back in right angular position with the inner hinged portion of the lower cover; a carrier plate provided with posts designed to telescope within the upright hollow posts, substantially as shown and described.

3. A loose leaf file comprising a back and upper and lower covers loosely secured together, each of said covers having a hinge near its inner end, a plate having orificed flanges on each of its ends, mounted on the upper surface of the lower cover and inside of the hinged portion thereof, said plate also having upwardly projecting posts secured thereto to engage perforations in the sheets to be bound, a wire spring overlying said plate, its ends projecting through the orifices in the flanges, said spring lying on the inner side of the upright posts, right angular plates joining rigidly at right angles the back and the inner hinged portion of the upper cover, each of said plates being provided with recesses to receive the ends of the wire spring and thereby secure the back in right angular position with the inner hinged portion of the lower cover, a carrier plate provided with posts designed to engage their respective perforations in the sheets to be bound, substantially as shown and described.

In testimony whereof, I have signed the foregoing specification.

CHARLES F. McBEE.
